DESIGN FOR A HIGH MODEL FOOT PLATFORM CHAIR

Roy A. Cramer and Jesse F. Cramer,
Kansas City, Mo.

Application December 22, 1939, Serial No. 89,090

Term of patent 3½ years

To all whom it may concern:

Be it known that we, Roy A. Cramer and Jesse F. Cramer, citizens of the United States and residing at Kansas City, Jackson County, Missouri, have invented a new, original, and ornamental Design for a High Model Foot Platform Chair, of which the following is a specification, reference being had to the accompanying drawing, forming a part hereof.

In the drawing, Figure 1 is a perspective view of a high model foot platform chair showing our

new design; and Figure 2 is a perspective view broken through the supporting legs to more clearly illustrate the parts not clearly shown in Figure 1. The characteristic features of our design reside in the portions shown in solid lines.

We claim:

The ornamental design for a high model foot platform chair, as shown and described.

ROY A. CRAMER.
JESSE F. CRAMER.
